AIR COMPRESSOR TANK DRAIN VALVE

Dewey Wilkerson, Denver, Colo., assignor to
 Wilkerson Corporation, Denver, Colo., a corpora-
 tion of Colorado

Application May 7, 1951, Serial No. 224,991

1 Claim. (Cl. 137—650)

1
 This invention relates to fluid pressure operated valves and particularly to an air pressure responsive valve for automatically draining off all accumulated water, oil, and sludge deposits in the air storage tank of an air compressor.

An object of the invention is to provide an air tank drain valve of simple, rugged construction operative from an intermitting pressure air line for the automatic expulsion at tank pressure of accumulations of water, oil, sludge and other foreign matter therein. Other objects will be apparent to persons skilled in the art.

It is to be understood that the instant disclosure is illustrative of one embodiment by which the invention is reduced to practice, and that any desired changes and modifications consistent with the scope of the invention as claimed may be made in the details of the structure as shown.

The single figure of the drawing is substantially a central vertical sectional view through a drain valve comprising the invention.

As here shown, my novel valve comprises a substantially frusto-conical housing made up of a base section 5, an intermediate section 6, a top section 7, and an attaching nipple 8 by which the valve is connected with the bottom of a compressed air storage tank 9. The housing interior is divided into three non-communicating compartments by a lower flexible diaphragm 11 between the base and intermediate sections and by an upper flexible diaphragm 12 between the intermediate and top sections. These diaphragms are clamped at their marginal portions between meeting edge flanges on the respective sections in the conventional manner of diaphragm mounting. The base 5 is dished from its upper face to constitute a lower air compartment 13 beneath the diaphragm 11, and the intermediate section 6 is oppositely dished from its bottom face to constitute an intermediate air compartment 14 between the two diaphragms. The interior of the top section 7 above the diaphragm 12 constitutes an upper air compartment 15 open to the atmosphere through a breather port 16 and closed at its top by a thickened wall portion 17 of the housing section 7.

The intermediate section 6 is formed with an integral interior wall 18 inset slightly from the top face of the section and provided with a central air passage 19. This wall forms a retainer for the upper end of an expansion spring 20 which bears at its lower end on a circular foot plate 21 that engages the central portion of the dia-
 phragm 11 to press it down flatly against the flat

2
 bottom of the air compartment 13. The bias of spring 20 is sufficient to maintain the diaphragm 11 flexed downwardly against the bottom of the compartment in the position shown when air in the compartment 13 is substantially at atmospheric pressure.

The base compartment 13 is adapted for open communication with an intermitting pressure air line, not shown, through an air inlet 21, and may 10 optionally be provided with a double acting check valve 22 controlling a drain cock 23 to the atmosphere. Air may enter the compartment 14 between the two diaphragms by way of an inwardly 15 opening check valve 24 in the wall of the section 6, and is bled to the atmosphere through an adjustable needle valve assembly 25 also in the wall of the section.

An axial drainage bore 26 is provided through the apex portion of the top section 7 in communication at its lower end through a port 27 with a radial sediment discharge passage 28 which opens to the atmosphere through the thickened wall portion 17 of the section. The port 27 is surrounded by a valve seat which receives a valve 29 on the upper end of an axial stem 30 mounted for reciprocation in the wall portion 17. The stem 30 extends within the compartment 15 and at its lower end carries a circular foot plate 31 which seats flatly on the diaphragm 12 and biases it to flex downwardly under the expansive force of a coil spring 32 which surrounds the stem. The lower end of the spring bears on the foot plate 31 and its upper end seats against a washer 33 nested in a recess in the underface of the wall portion 17. The washer serves also to retain in place a packing ring 34 of rubber or other suitable material around the valve stem to seal it against leakage from the passage 28 into the compartment 15.

40 The attaching nipple 8 has threaded connection with the apex portion of the section 7 and is externally threaded at its upper end for detachable connection in the bottom of the tank 9. An axial bore 35 extends through the nipple and receives therethrough an upper valve stem 36 co- 45 axial with the stem 30. The stem 36 is adapted for reciprocation in the bore 35 with ample clearance to provide free drainage from the tank into the relatively larger bore 26 of the top section of the housing. A valve 37 on the upper end of the stem cooperates with a seat on the upper end of the nipple 8 to control the bore 35; and adjacent its lower end the stem carries a cross pin 38 that provides a seat for the lower end of an expansion spring 39 surrounding the stem with its

upper end bearing against a shoulder formed by a lateral enlargement of the bore 35. The lower end of the stem 36 normally is spaced above the upper end of the stem 32.

In the illustrated normal position of the parts, the two valves 29 and 37 are closed tightly against their seats through the downward pull exerted on their stems by the respective springs 32 and 39, doubly closing the drain passage from the tank. The valve 28 constitutes an inner seal within the casing and the valve 37 constitutes a safety seal at the tank outlet. Also in the illustrated normal position, air in all three compartments 13, 14, and 15 is at atmospheric pressure. When air under intermittent source pressure enters the base compartment 13 through the inlet 21 it immediately flexes the diaphragm upwardly against the bias of the spring 29 and compresses the air in compartment 14. This compressed air acts through the aperture 19 to lift the diaphragm 12 and valve stem 30 and open the valve 29. During its upward travel the upper end of the stem 30 picks up and lifts the stem 36 to open the valve 37 and permit accumulated water, sludge, and oil on the tank bottom to blast at tank pressure through the passage comprising the bore 35, bore 23, and passage 22 to the atmosphere. The lower diaphragm remains in its upwardly flexed position for as long as source pressure continues in the compartment 13, which may be from a few seconds to several hours depending upon the type of installation.

Duration of the discharge blast from the tank is determined by appropriate adjustment of the needle valve 25 to regulate the rate at which air can escape from the compartment 14 and thus permit reseating of the valves 27 and 29 by action of their respective springs. As air bleeds from the compartment 14 the upper diaphragm 12 flexes downwardly, regardless of the position of the lower diaphragm 11, and the valve stems are correspondingly lowered until their respective valves are fully reseated, with the valve 37 closing slightly before the valve 29. This relative overtravel between the two valves permits full drainage of the discharge passage and assures closure thereof even though one valve should for some reason fail to seat properly at the time. When the intermittent line source pressure in the compartment 13 is relieved, the spring 28 immediately flexes the diaphragm downwardly to its original position, with the check valve 24 opening automatically to allow entry of air from the atmosphere behind the diaphragm if inflow past the needle valve 25 is insufficient.

An important feature of the invention is the fact that return of the upper diaphragm 12 to its original position, with consequent reseating of the valves 28 and 37, is governed entirely by release of air past the valve 25, which can be set for any desired time interval. Nothing mechanical can interfere with return of the diaphragm, and it is unaffected by pressure conditions in the line compartment 13.

From the foregoing description it is apparent that in its broad aspects the invention embodies a pair of valves spaced apart axially in the tank drain passage and spring loaded to close in the

direction of discharge flow therethrough. One valve has an overtravel relative to the other and also constitutes an actuator for moving it to open position. The actuator valve operates in response to pressure differential in two compartments in one of which air from the ambient atmosphere is compressed by the application of air at line pressure in the other to provide fluid motor means for moving the actuator valve, and through it the other valve, to open position. A third compartment has a collapsible wall flexing under air pressure in the motor compartment to move the valves into open position, from which they return to closed position under their spring bias at a rate of travel determined by the regulated escape of compressed air from the motor compartment.

I claim:

20 A compressed air tank drain valve comprising a housing having a base section, a top section, and an intermediate section, said base section having an inlet for communication with an intermittent pressure air line, said base and intermediate sections being oppositely dished from their adjacent faces, a first diaphragm secured between the base and intermediate sections and separating their interiors into a first compartment in open communication with the air inlet and a second compartment in restricted communication with the ambient atmosphere, a second diaphragm secured between said intermediate and top sections as a wall of said second compartment, said top section having a tank drain passage therethrough and a valve controlling said 25 passage, means in said top section common to both said valve and said second diaphragm and biasing the valve to closed position and said second diaphragm to a position of flexion inwardly of said second compartment, means in said second compartment biasing said first diaphragm to a position of flexion outwardly of the second compartment and into the first compartment, said first diaphragm flexing into the second compartment in response to application of air at line 30 pressure through said air inlet whereby to compress the air in the second compartment and thereby flex said second diaphragm outwardly to open said drain passage valve, and an air release valve in a wall of said intermediate housing section adjustable to regulate release of compressed air from said second compartment and thereby determine the rate of closure of the drain passage valve in response to its biasing means.
